LOOPER-ACTUATING MECHANISM FOR
SEWING MACHINESRudolph Becker, North Plainfield, N. J., assignor
to The Singer Manufacturing Company, Elizabeth, N. J., a corporation of New Jersey

Application November 28, 1945, Serial No. 631,302

16 Claims. (Cl. 112—199)

1

This invention relates to chain-stitch sewing machines of the type employing a thread-carrying needle and a cooperating oscillatory thread-carrying looper.

The invention has as a primary object to provide improved actuating means for the looper, whereby the looper will have a path of movement which will greatly facilitate the taking, holding and shedding of the needle-thread loop.

Another object of the invention is to provide an improved variable speed looper-actuating means which will move the looper at a decelerating speed during the latter portion of its loop-seizing stroke and at an accelerating speed during the major portion of its loop-shedding stroke.

A further object is to provide an improved variable speed looper-actuating mechanism and so to coordinate the movements of the looper with the movements of the needle that the stroke of the looper may be greatly reduced, as compared with prior constructions.

Still another object is to provide an improved looper-actuating mechanism which is particularly well adapted for wide gauge and multiple needle sewing machines.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings,

Fig. 1 is a front side elevation, partly in section, of a chain-stitch sewing machine embodying the present invention, with certain parts omitted for the sake of clearness.

Fig. 2 is an enlarged plan view of a portion of the machine base and the parts carried thereby, with certain cover plates and portions of the work-feeding mechanism omitted.

Fig. 3 is an enlarged transverse sectional view taken substantially on the line 3—3 of Fig. 2, and showing additionally certain elements of the work-feeding mechanism which are omitted from Fig. 2.

Fig. 4 is an enlarged transverse sectional view taken on the line 4—4 of Fig. 2.

Figs. 5, 6, 7 and 8 are a series of views of the needle and looper of the machine at different successive stages of a stitch-forming cycle.

Fig. 9 is an enlarged diagrammatic view illustrating the path of movement of the looper in

2

conjunction with various positions of the needle; the looper being indicated in the positions to which it is moved by successive angular movements of thirty degrees each of the main shaft of the machine.

Fig. 10 is a diagrammatic view illustrating the action of a loop-spreader, later to be described, in conjunction with the looper and the needle.

Fig. 11 is an enlarged sectional view taken substantially on the line 11—11 of Fig. 2.

Referring more specifically to the drawings, the invention is disclosed as embodied in a sewing machine having a frame comprising a pan-like bed or base 15, a standard 16 and an overhanging bracket-arm 17 terminating in a bracket-arm head 18. Journaled in bearings 19, lengthwise of the bracket-arm, is a main or arm shaft 20 carrying, at its rear end, a combined belt and hand wheel 21 through which the shaft 20 is driven from any suitable source of power.

Mounted in the head 18, for endwise reciprocation, are two needle-bars 22, each having secured to its lower end, a block 23. Secured in and extending through the blocks 23 are two horizontally disposed rods 24 upon which may be adjustably secured a plurality of needle-carrying blocks 25 each generally similar to the blocks 23. Each of the blocks 25 is adapted to carry a needle N, only three of which are shown. Any suitable number of needle-carrying blocks 25 may be mounted upon the rods 24 and, by adjusting them along the rods and securing them thereto, any desired spacing of the needles and consequently any desired spacing of the seams formed thereby may be obtained.

Cooperating with each of the needles in the formation of stitches, is a thread-carrying chain-stitch looper L, also of which only three are shown. Each of the loopers L is secured in an oscillatory looper-carrier 26 in proper position to cooperate with its complemental needle. The looper-carrier, and the loopers carried thereby, are given oscillatory and orbital movements from a rotary feed and looper actuating shaft 27, journaled in bearings 28 in the base, through mechanism hereinafter to be described.

The shaft 27 is rotated from the main shaft 20 through the medium of a one-to-one pulley and clip-belt drive, located in a vertically disposed cavity 16^a in the standard 16, and comprising a slotted pulley 20^a on the shaft 20, a similar pulley 27^a on the shaft 27 and a clip-belt 20^b connecting these pulleys.

The needle-bars 22, and the needles carried thereby, are given endwise reciprocations from

the arm shaft 20 through mechanism designated generally as *x*, and in timed relation with the movements of the loopers.

Secured upon the upper side of the base 15 are suitable cover plates 15^a and a work-supporting throat-plate 28 having therein slots 29 through which operate the feed-dog 30 forming a part of a lower four-motioned work-feeding mechanism portions of which are shown and designated generally as *f*. During the time that the feed-dog is below the upper face of the throat-plate, the work is held on the throat-plate by two presser-feet 31 (of which one is shown) each pivotally mounted upon a shank 31^a, secured to the lower end of a spring-depressed presser-bar (not shown) mounted in the head 18.

The feeding mechanism may be of any suitable or preferred construction, such, for example, as that disclosed in my United States Patent No. 2,409,242, October 15, 1946.

The looper-carrier 26 is formed in its ends with transverse grooves 32 and 33 which receive tongues 34 and 35, respectively, formed on the adjacent ends of aligned looper-driving shafts 36 and 37. The looper-carrier is secured to the shafts 36 and 37 by clamp screws 38, carrying washers 39, and set screws 40. Each looper is formed with a depending cylindrical shank *s*, fitted into a bore *b* in the looper-carrier 26 and held therein by a set screw 41. The lower end portion of each looper shank is formed with a transverse thread aperture 42 which moves relative to and cooperates with fixed thread-guides 43 and 44, to pull looper thread *t* from the supply and to serve as a take-up for the looper thread. The thread-guides 43 and 44 are carried, respectively, by angle-bars 45 and 46 secured to the base 15 of the machine.

The looper-carrier 26 and the shafts 36 and 37 form, in effect, a single composite looper-carrying and -actuating shaft, the portion 26 being made removable from the portions 36 and 37 so that it may be removed and interchanged with other similar portions each having a different arrangement of looper-receiving bores *b*, whenever it is desired to employ a different number or spacing of needles and loopers.

To the end that the composite looper shaft 36, 26, 37, be operated smoothly and without any binding or cramping action, means is provided for actuating the shaft synchronously from each end thereof, as hereinafter will be described.

The looper shaft sections 36 and 37 are journaled, respectively, in eccentric bores 47 and 48 formed in bushings 49 and 50 which carry eccentric gears 51 and 52. The bushings 49 and 50 are journaled in bearing sleeves 53 and 54 secured in the base of the machine. The bushings 49 and 50 are held against endwise movement in one direction by hubs on the gears 51 and 52 abutting the outer ends of the bearing sleeves and in the other direction by disks 53^x and 54^x secured to the bushings 49 and 50 and bearing against annular shoulders 49^x and 50^x provided by the sleeves 53 and 54, respectively. Collars 36^x and 37^x, secured upon the shaft sections 36 and 37 and abutting the disks 53^x and 54^x, hold the composite looper shaft against endwise movement.

Secured eccentrically upon the shaft 27 are 70 two looper-driving gears 55 and 56 complementary to and driving, respectively, the gears 51 and 52 on the composite looper-actuating shaft. Thus rotation of the shaft 27 effects, through the eccentric gears 55—51 and 56—52, rotation, at a

varying rate, of the bushings 49 and 50 in their bearing sleeves 53, 54, thereby moving the composite looper-actuating shaft laterally of its axis in an orbit or around a field which is designated *y* in Figs. 4, 5, 6, 7 and 8.

During the variable speed rotation of the looper-shaft about the field *y* the looper shaft is also oscillated on its own axis. This oscillation is effected by an eccentric or crank 57 formed on the shaft 27 and embraced by a split block 58, having in its lower portion a cylindrical bore 59. Slidably fitted within the bore 59 is a pin 60 formed integral with a split head 61 secured by screws 62 and 63 upon the portion 37 of the looper-actuating shaft.

Figs. 5, 6, 7 and 8 show one of the needles, and its complemental looper, and the supporting and actuating mechanism for the looper in different successive positions which they assume during the formation of a stitch. These positions correspond, respectively, to the positions of the looper numbered 2, 5, 9 and 11 in Fig. 9 in which the entire cycle of the looper and the path of travel of the looper-eye together with the corresponding positions of the point of the needle are illustrated on an enlarged scale.

Assume now that in Fig. 9 the needle is carrying an upper thread *n* and the looper is carrying a lower thread *t*, as in Figs. 5, 6, 7 and 8, with the lower thread passing through a first eye *e* in the heel of the looper, then extending along a groove in the blade thereof and finally back through an eye *e'* adjacent the point of the looper, as shown in Fig. 10. Assume further that the needle has penetrated the work and has carried its thread with it to its lowermost position, indicated as 0 (zero) in Fig. 9. The looper is substantially in its most retracted position, also as indicated by the position 0 (zero) of the looper eye *e'*. Successive turning movements of the main shaft 20 of thirty degrees each move the looper-eye and the needle successively to the positions designated as 1, 2, 3, 4, 5, 6, 7, 8, 9, 10, 11 and finally back to zero. During the first sixty degrees rotation of the main shaft, the needle is retracted from zero position to the position designated as 2, during which it casts out a loop *l* of the needle thread. The looper advances from zero position to the position numbered 2 in Fig. 9 and, as shown in Fig. 5, enters the needle-thread loop *l*. The next ninety degrees rotation of the main shaft retracts the needle and advances the looper to the positions numbered 5 in Fig. 9, and shown in Fig. 6, thereby carrying its thread through the needle-thread loop and retaining thereon the needle-thread loop which slides along the looper-blade and into the throat thereof as shown in Fig. 6.

In advancing from zero position to position Number 4, the looper moves forwardly and downwardly, at a rapid rate, in a substantially straight path, thus greatly facilitating the taking of the needle-thread loop.

The looper moves slowly between positions 4 and 7, thereby giving the needle time to retract from its Number 4 position to its uppermost position (Number 6), to reverse its direction of movement and to advance to position Number 7.

The looper is then retracted rapidly from position 7 to position 9, which is shown in Fig. 7. During this movement the looper rolls upwardly and backwardly, thereby facilitating its partial withdrawal from the needle-thread loop which is then held around the blade of the looper. Also during this movement, the looper thread *t*

is engaged by a laterally movable spreader finger 65, later to be described, which moves a portion of the looper-thread laterally, as shown in Fig. 10, thereby forming a triangle between the looper thread and the blade of the looper into which triangle the needle descends and carries its thread.

A further sixty degree rotation of the main shaft retracts the looper from the position 9, shown in Fig. 7, to the position 11, shown in Fig. 8, 10 thus causing the looper to shed the previously engaged needle-thread loop which thereupon is drawn up and tightened by the needle-thread take-up, thereby completing the concatenation of the two threads in a two-thread chain-stitch. After the needle has entered the looper-loop, re-15 tracting of the looper effects a relative movement between the thread-eye 42, in the shank s of the looper, and the fixed thread guides 43 and 44, thereby tightening the stitch and drawing looper 20 thread from the supply.

Due to the fact that the looper is moved upwardly toward the throat-plate during its retractive loop-shedding movement, the point of the looper is closely adjacent the work when the 25 needle-loop is shed from the looper, thereby requiring very little take-up action to tighten and set the stitch.

In its final descent, the point of the needle passes between spaced walls of a sheet metal 30 needle guide 66 carried by the shank of the looper, which guide insures the proper positioning of the needle for the taking of the next needle-loop by the loop-taker.

The final thirty degrees of rotation of the main shaft moves the needle and looper from their number 11 position back to zero position preparatory to the beginning of a new cycle of 35 operation.

The spreader 65, hereinbefore referred to, of which there are as many as the number of loopers employed, is secured to a horizontally disposed member 67 slidably mounted in a channel 68 in the under side of the throat-plate 28. At one end the member 67 is connected to a slide-bar 69 slidably mounted within a slideway 70 formed in the under side of a block 71 secured to the base of the machine. The slide-bar carries a roller-stud 72 which tracks a cam-groove 73 formed in a cam-disk 74 secured to the face of 50 the gear 51, as by screws 75.

Having thus set forth the nature of the invention, what I claim herein is:

1. In a two-thread chain-stitch sewing machine having a reciprocatory eye-pointed needle, a 55 thread-carrying looper formed with a blade having a loop-seizing beak, means to move said looper in an orbit about a field parallel to the needle, and means to oscillate said looper in the plane of and in time with its orbital movement so that the looper-blade moves in a downwardly inclined substantially straight path when advancing to seize a needle-loop and has an upwardly inclined movement in a curved path above the first named path when shedding the needle loop.

2. In a two-thread sewing machine, the combination with a reciprocatory eye-pointed needle, of a thread-carrying looper having a loop-seizing beak, and means including an eccentric gear 70 drive to impart variable speed needle-loop-seizing and -shedding movements to said looper around a field parallel to said needle, while so oscillating the looper in the plane of said field as to give the looper a downwardly inclined substantially 75

straight path of movement during its loop-seizing movement and an upwardly inclined curved path of movement during its shedding of the loop.

3. A looper-mechanism for cooperation with the reciprocatory eye-pointed needle of a two-thread chain-stitch sewing machine comprising, a thread-carrying looper, a looper-carrying shaft, and a variable speed driving means to move said shaft bodily sidewise at a varying rate around a field while oscillating said shaft on its own longitudinal axis.

4. A loop-taking mechanism for two-thread sewing machines comprising, a rotary member, an oscillatory shaft carried by said rotary member eccentrically of and parallel to the axis of rotation of the latter, variable speed means to drive said rotary member, means to oscillate said shaft, and a thread-carrying looper mounted on said shaft.

5. A two-thread chain-stitch sewing machine looper-mechanism comprising, a frame, a rotary shaft journaled therein, an eccentric carried by said shaft, a strap surrounding said eccentric and affording a tubular bore, a rotary bushing journaled in said frame, a pair of eccentrically journaled gears connecting said shaft with said bushing to rotate the bushing at a variable rate, a looper-shaft journaled eccentrically in said bushing, a pin fixed to said looper-shaft and fitted into the bore in said eccentric strap to effect oscillation of said looper-shaft by said eccentric, and a thread-carrying looper mounted on said looper-shaft.

6. A mechanical movement for a sewing machine looper comprising, a driving shaft, an eccentric fixed thereon, a rotatable eccentric bushing, a first eccentric gear secured to said driving shaft, a second eccentric gear, complementary to the first, secured to said bushing, said gears rotating said bushing at a variable rate from a constant rate of rotation of said driving shaft, a second shaft journaled in said bushing, a sleeve embracing said eccentric and connected to oscillate said second shaft, and a thread-carrying 40 looper carried by said second shaft for variable speed movements about a field.

7. In a sewing machine, a shaft, an eccentric gear drive to move said shaft at a varying rate laterally of its axis about a field, means to impart movements of oscillation to said shaft while the latter is being carried around said field, and a thread-carrying loop-taker carried by said shaft.

8. In a two-thread chain-stitch sewing machine having a reciprocatory thread-carrying needle, a thread-carrying looper and means to first move the looper in a substantially straight line inclined downwardly to project the looper and its thread through the needle thread loop, then to retract the looper and, simultaneously with the retracting movement, to move the looper upwardly and tip it backwardly until the needle has passed its loop through the looper-loop, and finally to lower the looper to initial position ready for projection into the next needle-loop.

9. In a two-thread chain-stitch sewing machine having a reciprocatory eye-pointed needle, a thread-carrying looper formed with a blade having a loop-seizing beak, means to move said looper in an orbit about a field parallel to the needle, and means to oscillate said looper in the plane of and in time with its orbital movement so that the beak of the looper-blade moves in a substantially plano-convex path in a vertical

plane during the seizing and shedding of the needle-thread loop.

10. In a two-thread sewing machine, the combination with a reciprocatory eye-pointed needle, of a thread-carrying looper having a loop-seizing beak, and means to impart variable speed needle-loop-seizing and -shedding movements to said looper around a field parallel to said needle, while so oscillating the looper in the plane of said field as to give the looper beak a downwardly inclined substantially straight path of travel during its loop-seizing movement and an upwardly convex path of travel during its loop-shedding movement.

11. In a sewing machine having a frame including a base provided with spaced vertically disposed walls, a rotary drive shaft journaled in bearings in said walls, a rotary bushing journaled in each of said walls and in alignment with each other, a variable speed driving connection from said shaft to each of said bushings, a looper shaft journaled eccentrically in said bushings and rotatable therewith sidewise about a field, a thread-carrying looper carried by said looper shaft, and means actuated by said drive shaft for oscillating said looper shaft during its rotation with said bushings, to cause said looper to be moved in an orbital path at a varying rate.

12. In a sewing machine having a frame including a base provided with spaced vertically disposed walls, a rotary drive shaft journaled in bearings in said walls, a rotary bushing journaled in each of said walls at one side of and parallel to said shaft and in alignment with each other, an eccentric gear driving connection from said shaft to each of said bushings, a looper shaft journaled eccentrically in said bushings and rotatable therewith sidewise about a field, a thread-carrying looper carried by said looper shaft, and means actuated by said drive shaft for oscillating said looper shaft during its rotation with said bushings, to cause said looper to be moved in an orbital path at a varying rate.

13. In a sewing machine having a frame including a base provided with spaced vertically disposed walls, a rotary drive shaft journaled in bearings in said walls, a rotary bushing journaled in each of said walls and in alignment with each other, a driving connection from said shaft to each of said bushings, a looper shaft journaled eccentrically in said bushings and rotatable therewith sidewise about a field, said looper shaft extending between said spaced walls, a plurality of thread-carrying loopers carried by that portion of the looper shaft between said walls, and means actuated by said drive shaft for oscillating said looper shaft during its rotation with said bushings, to cause said loopers to be moved in an orbital path.

14. In a sewing machine having a frame including a base provided with spaced vertically disposed walls, a rotary drive shaft journaled in bearings in said walls, a rotary bushing journaled in each of said walls and in alignment with

each other, a driving connection from said shaft to each of said bushings, a looper shaft journaled eccentrically in said bushings and rotatable therewith sidewise about a field, said looper shaft extending between said spaced walls and having a portion thereof bodily removable from the portions journaled in the bushings, a plurality of thread-carrying loopers carried by the removable portion of said looper shaft, and means actuated by said drive shaft for oscillating said looper shaft during its rotation with said bushings, to cause said loopers to be moved in an orbital path.

15. In a two-thread chain-stitch sewing machine having a frame including a base provided with spaced vertically disposed walls, a reciprocatory thread-carrying needle, a rotary drive shaft journaled in bearings in said walls, a rotary bushing journaled in each of said walls and in alignment with each other, a driving connection from said shaft to each of said bushings, a looper shaft journaled eccentrically in said bushings and rotatable therewith sidewise about a field, a thread-carrying looper carried by said looper shaft, means actuated by said drive shaft for oscillating said looper shaft during its rotation with said bushings, to cause said looper to be moved in an orbital path, a cam secured to and rotatable with one of said bushings, a bar slidably mounted in one of said walls and operatively connected with said cam to be reciprocated thereby, and a loop-spreader carried by said bar and movable horizontally between the needle and the looper, to form a bight in the looper thread for entrance by the needle.

16. In a two-thread chain-stitch sewing machine having a throat-plate provided with a needle-hole, a reciprocatory thread-carrying needle operating through the needle-hole, a thread-carrying looper cooperating with said needle in the formation of stitches, and means to move the looper at a varying rate first in a substantially straight line inclined downwardly toward the front of the machine to project the looper and its thread through the needle-thread loop, then to retract the looper and, simultaneously with the retracting movement to move the looper upwardly and backwardly in a curved path until the needle has passed its loop through the looper-loop, and finally to lower the looper to initial position ready for projection into the next needle-loop, the looper being considerably closer to said needle-hole when shedding the needle-loop than when entering the same.
